8 Claims. (Cl. 177—353)

1

The present invention relates to a scanning system which in particular makes it possible to select a circuit from one or more groups of circuits, the scanning operation being effected by simple means and in an extremely short time.

One of the features of the invention is the employment of static electrical means in order automatically to test the electrical condition of a plurality of circuits to which said static means have access and to effect a selection of one circuit in a particular group of said circuits.

Another characteristic of the invention is the testing in a predetermined order by static electrical means of a certain number of circuits divided up into several groups, arrangements being provided for controlling the order of scanning of the circuits, for proceeding successively with the identity testing of each of the circuits in terms of the grouping of said circuits, and for testing the electrical condition of the circuits.

Another characteristic of the invention consists in a system for scanning one or more groups of circuits and selecting one circuit in a particular group, and for recording the identity of the selected circuit, and for effecting, under the control of the registering device, the operations of connection of the selected circuit.

Another feature of the invention consists of a selection system for selecting one circuit in one or more groups of circuits, in which several stages of time positioned control impulses are employed to control the scanning.

Another characteristic of the invention consists of a device for selecting one circuit in a set of groups of circuits and comprising a group of electrical switches, the number of said electrical switches being equal to the maximum number of circuits in a group and their arrangement being provided on the one hand in order to control the selection of the group of circuits and on the other hand in order to control the selection of one circuit in the selected group.

Another characteristic of the invention consists of a device for selecting one circuit in a set of groups of circuits and comprising a group of thermionic or gas discharge devices, each device comprising several electrodes, the number of devices in each group being equal to the maximum number of circuits in one group, and their arrangement being provided in order on the one hand to control the selection of the group of cir-

cuits and on the other hand to control the selection of one circuit in the selected group.

The essence of the invention and various other characteristics will appear from the following description given as a non-limitative example with reference to the attached drawings, in which:

Fig. 1 shows a selection control circuit comprising a group of cold cathode tubes for the purpose of selecting a free circuit in a certain number of groups of circuits which may, for example, be the outlets of one selection stage in an automatic telephone exchange.

Fig. 2 shows the potential impulse curves of two different orders employed in the circuit arrangement of Fig. 1.

Referring to Fig. 1, two groups of cold cathode tubes $Va1$ to $Va3$ and $Vb1$ to $Vb3$, have been provided, each comprising an anode, represented by a small circle, a cathode connected through a contact $cx1$ or $cx2$ and a resistance $R1$ or $R2$ to the batteries $B1$ or $B2$, each of these batteries being assumed to have a voltage of 150 v., and a control electrode connected to the signalling or marking wire MW .

It has been assumed that the selection is to be made in a set of three groups of circuits each comprising three circuits $C11$ to $C13$, $C21$ to $C23$ and $C31$ to $C33$. The circuit elements shown consist of the test wires of the various circuits, in each of which is inserted a busy contact $BC11$ to $BC13$, $BC21$ to $BC23$, $BC31$ to $BC33$.

The test wires of each of the first circuits in each group are connected through unidirectional current carrying devices, such as rectifiers, for example, $RC11$, $RC21$, $RC31$ to the common wire $IW1$. Similarly, the test wires of the second circuits of the different groups are connected via the rectifiers $RC12$, $RC22$, $RC32$ to the common wire $IW2$, while the test wires of the third circuits of the different groups are connected via the rectifiers $RC13$, $RC23$ and $RC33$ to the common wire $IW3$.

Two different ways of connecting wires $IW1$, $IW2$, and $IW3$ to the control electrodes of the group of cold cathode tubes $Vb1$ to $Vb3$ are shown in Fig. 1, said wires may be either connected individually to the control electrode of each of the tubes through the wires $TW1$, $TW2$, $TW3$, as indicated in dotted lines, or, through a simple test wire TW as indicated below.

The operation of the system will first of all be

described on the assumption that the wires **IW1**, **IW2**, **IW3** are respectively connected to the wires **TW1**, **TW2**, **TW3**.

The selection of a group of lines and the selection in the group of lines is entirely controlled by the group of tubes **Vb1** to **Vb3**. The purpose of the tubes **Va1** to **Va3** is to register the identity of a selected group of circuits by the operation of one of the tubes corresponding to the selected group. The tubes **Vb1** to **Vb3** are not only intended to control the selection but also to register the identity of the selected circuit in a selected group, and thus it is by the operation of the first, second or third tube which respectively corresponds to the first, second or third circuit of each of the groups.

In the anode circuit of each of the tubes a relay **Ra** or **Rb** is inserted; the relay **Ra1** comprises the contact **Ra11**, relay **Ra2** the contact **Ra21**, relay **Ra3** the contact **Ra31**; relay **Rb1** comprises the contacts **Rb11**, **Rb12** and **Rb13**; and relay **Rb2** comprises the contacts **Rb21**, **Rb22** and **Rb23**, and relay **Rb3** the contacts **Rb31**, **Rb32** and **Rb33**. The combination of these different relay contacts makes it possible to apply earth to one of the wires **I-9** corresponding to the three circuits of the three groups, in accordance with the group and line selected.

The various circuits among which the selection is to be operated, are characterized by time positioned impulses which are applied thereto. These impulses are repetitive impulses with a repetition rate which is the same for each circuit. The time duration of each impulse is short with respect to the time between impulses, and the impulses characterising each group of circuits are spaced in time from those characterizing any other group. These impulses are represented at φ_1 , φ_2 , and φ_3 in Fig. 2, and, as shown, produce potentials of -50 volts during the period of the impulse, while the potential changes to -100 volts between impulses. These impulses are produced in a known manner by the three generators indicated in Fig. 1 as φ_1 generator, φ_2 generator, φ_3 generator. Potential impulses in accordance with a periodic cycle φ_1 , φ_2 , and φ_3 , the number of impulses per cycle being equal to the number of groups of circuits, are applied to the test wires of the circuits from the impulse generators, each of the generators being assigned to a different group and the impulses thereof sent to each of the test wires in the group. Marking wire **MW** is connected at its end to a mobile or wiper contact **sc** in order selectively to connect said **MW** to one of the contacts **Pt1**, **Pt2** or **Pt3** on which are also received the same potential impulses φ_1 , φ_2 , and φ_3 used to mark the groups of circuits. These same impulses φ_1 , φ_2 , and φ_3 are also applied respectively to the control electrodes of the tubes **Va1**, **Va2**, and **Va3**.

Another set of potential impulse generators labelled **P1** generator, **P2** generator and **P3** generator, in Fig. 1, producing repetitive impulses **P1**, **P2**, and **P3** at a submultiple rate with respect to the rate of the impulses φ_1 , φ_2 , and φ_3 is also employed. Each of the impulses of these generators has a time duration equal to that of a complete cycle of impulses φ_1 , φ_2 , and φ_3 . In the simple selective system shown, these impulses repeat at one third the rate of the impulses φ_1 , φ_2 , and φ_3 ; in other words there is one cycle for every three cycles of φ_1 , φ_2 , and φ_3 . The impulses **P1**, **P2**, and **P3** are spaced in time with respect to each other, as will be seen from Fig. 2, and have a potential of -50 volts, while between

impulses the potential is -100 volts. The individual impulses **P1**, **P2**, and **P3** are respectively applied to the control electrodes of the tubes **Vb1**, **Vb2**, **Vb3**.

It has been assumed that when a potential impulse is not sent, the potential of the source is -100 v.; under these conditions the potential applied to the control space of a tube is insufficient to cause it to be ionized, since the difference of potential between the cathode and the control electrode is only 50 v. At regular intervals, however, when the impulses are applied, the voltage of the control electrode may be raised to -50 volts making a difference of potential of 100 volts between the control electrode and the cathode. This potential can cause ionization of the tube if the contact **cx** of its cathode is closed.

For the operation of the tubes **Va** and **Vb** the potentials of -100 v. are ineffective control potentials, while potentials of -50 v. are effective control potentials.

The connections to the control electrodes are not made directly, but through resistances and rectifiers. For each of the individual control electrodes a connection is made through a resistance, while any other connections are made through a rectifier or rectifiers. Tube **Va1**, for example, has its control electrode connected to the **NW** wire through rectifier **Rga1**, while the φ_1 impulse is applied to this electrode through resistance **Rha1**. Tube **Va2** has its control electrode connected through rectifier **Rga2** to the **MW** wire and to the source of φ_2 impulses through resistance **Rha2**. Tube **Va3** has its control electrode connected through rectifier **Rga3** to the **MW** wire and to the source of φ_3 impulses through resistance **Rha3**. Tube **Vb1** has its control electrode connected to the source of **P1** impulses through rectifier **Rcgb1**, to the **MW** wire through rectifier **Rcgb1**, and to the **TW1** (or **TW**) wire through a resistance **Rhb1**. Tube **Vb2** has its control electrode connected to the source of **P2** impulses through rectifier **Rcgb2**, to the **MW** wire through rectifier **Rcgb2**, and to the **TW2** (or **TW**) wire through resistance **Rhb2**. Tube **Vb3** has its control electrode connected to the source of **P3** impulses through rectifier **Rcgb3**, to the **MW** wire through rectifier **Rcgb3**, and to the **TW3** (or **TW**) wire through resistance **Rhb3**.

The general rule for connections to control electrodes in that any number of impulse sources may be connected to each control electrode without mutual interference of the different sources and/or tubes, provided only that each of the control electrodes is connected to one source through a resistance and to all the others through a rectifier peculiar to each of them. The source connected through the resistance acts as a source from which the current is supplied to effect an ionization of the discharge gap, the other sources which are connected to the same gap through rectifiers never supply current, but only absorb the current supplied by the source connected through the resistance during the time in which the potential of the latter is effective, and at least one of the absorbent sources ineffective. For this reason the rectifiers must be poled so as to permit current to flow through the resistance from the source connected thereto.

Assume that the potential applied to the resistance connected to the control electrode of a tube is -50 volts because at that instant the impulse from one of the sources is applied thereto. Then at that instant if the potential applied to the other terminal of one of the rectifiers con-

nected to the same control electrode is -100 volts, which is the voltage from any of the sources at the time between impulses, then current will flow through the resistance causing the control electrode to assume a potential of -100 volts and preventing the firing of the tube. If, however, the potential applied to the outside terminals of all of the rectifiers connected to the control electrode were -50 volts at this time, the rectifiers would be blocked and no current could flow through the resistance. The control electrode would therefore have a voltage of -50 volts applied to it, and since there would then be a difference of 100 volts between the control electrode and the cathode the tube would fire. In order for a tube to fire, therefore, it must have -50 volts applied to the resistance and all rectifiers connected to the control electrode. This can only happen when the impulses applied to the resistance and to all the rectifiers coincide.

Instead of three groups each of three circuits, there might be any number of groups with any number of circuits as desired, for example, ten groups each of ten circuits, the number of the tubes being provided accordingly, that is to say, ten tubes Va and ten tubes Vb , the number of impulse trains of Fig. 2 being increased accordingly.

The operation of the system for selecting a free circuit in a desired group will now be explained. When the device is seized for use, the contacts $cx1$ and $cx2$ are closed. The mobile contact sc is moved in any desired manner not shown, on to one of the contacts $Pt1$ to $Pt3$, to determine the group of circuits in which selection is to be made; it will be assumed that sc has been moved on to contact $Pt2$ and that consequently the impulses $\varphi2$ are sent on the wire MW .

It will be assumed that the device has been put into use just before the impulses $\varphi1$ and $P1$ are generated. When the first $\varphi1$ impulse is generated, the potential of -100 v. on the test wires of the No. 1 circuits of all the groups is replaced by a potential of -50 v.

The only one of the Va tubes which has the $\varphi1$ impulses connected to its control grid is $Va1$, but at the instant of the $\varphi1$ impulse the MW wire has -100 volts on it, since the $\varphi2$ impulse has not yet been generated. Current will therefore flow through resistance $Rha1$ and the potential on the control electrode will be -100 volts, the same potential that is on the MW wire. The control electrodes of tubes $Va2$ and $Va3$ have -100 volts on them.

Let us consider tube $Vb1$, since the impulse $P1$ coincides in time with $\varphi1$, a potential of -50 v. is sent from impulse $P1$ generator to the rectifier $Rcub1$ and, if the first line of group No. 1 is free, that is to say, $BC11$ closed, -50 v. will be sent from $\varphi1$ impulse generator, via the wire $C11$, contact $BC11$ closed, $Rc11$, wire $IW1$, wire $TW1$, to the resistance $Rhb1$. At the same moment wire MW is at -100 v. potential, and under these conditions rectifier $Rcgb1$ is conductive and current will flow from wire $TW1$, via $Rhb1$, $Rcgb1$ to the source $\varphi2$; the drop of potential in resistance $Rhb1$ maintains the control electrode of $Vb1$ at -100 v. and said tube cannot be ionized.

The -100 v. potential is sent to the control electrode of tube $Vb2$, via resistance $Rhb2$, via $TW2$, $IW2$, and the No. 2 circuit of any group not busy, since all of these free circuits have 100 v. on them at this time. The rectifiers $Rcgb2$ and $Rcub2$ have -100 v. on them, but even if they had -50 v., the tube cannot be

ionized because of the polarity of the rectifiers. Similarly the potential of the control electrode of $Vb3$ is maintained at -100 v.

Impulse $\varphi1$ being followed by impulse $\varphi2$ from the $\varphi2$ generator, -50 volts is now applied to the MW wire from the $\varphi2$ generator over $Pt2$ and Sc . The only Va tube with impulse $\varphi2$ applied to its control electrode circuit is $Va2$. Since -50 volts is applied to the rectifier $Rcga2$ from the MW wire and to the resistance $Rha2$, no current will flow through $Rha2$ and the control electrode will be raised to -50 volts potential. This fires tube $Va2$. Current then flows from ground, through relay $Ra2$, anode and cathode discharge gap of $Va2$, contact $cx1$ closed, resistance $R1$, battery $B1$, to ground. The tube $Va2$ is maintained fired and the drop in potential across resistance $R1$ lowers the potential on the cathodes of tubes $Va1$ and $Va3$ so that these tubes can no longer be ionized. The -50 v. potential is also sent, assuming the first line of group No. 2 to be free, to resistance $Rhb1$, through $C21$, contact $BC21$ closed, rectifier $RC21$, wire $IW1$, wire $TW1$. The -50 v. potential is simultaneously received from wire MW on rectifier $Rcgb1$, and directly on rectifier $Rcub1$ from the $P1$ generator. Under these conditions, since both rectifiers are blocked, tube $Vb1$ will operate, and cause the holding of relay $Rb1$. The flow of current in the circuit: earth, relay $Rb1$, anode and cathode of $Vb1$, and contact $cx2$, resistance $R2$, battery $B2$ maintains on the one hand the tube $Vb1$ fired at the end of the reception of the impulse $\varphi2$ and on the other hand causes a drop of potential in the resistance $R2$ which applies the cathodes of $Vb2$ and $Vb3$ to such a potential that said tubes can no longer be ionized.

It will be noted that although a potential of -100 v. is sent in each time unit to two of the three test wires in parallel $C11$, $C21$, $C31$ — $C12$, $C22$, $C32$ and $C13$, $C23$, $C33$, the potential of -50 v. received on the third test wire is effectively received on the corresponding wire $IW1$, $IW2$ or $IW3$ owing to the action of rectifiers $Rc11$ to $Rc13$, $Rc21$, to $Rc23$, $Rc31$ to $Rc33$ inserted in the circuit for connection of each of the test wires of the circuit to the wires IW . If all the circuits are free, the -50 v. potential is effectively transmitted to all the wires $IW1$, $IW2$, $IW3$ for the different impulses $\varphi1$, $\varphi2$, $\varphi3$; if certain circuits are busy, the contact BC associated with said circuits is opened, and the corresponding impulse cannot be received on wire IW .

If circuit $C21$ were busy, the tube $Vb1$ could not operate during the reception of the impulse $\varphi2$ because there would be no -50 volts on the resistor $Rhb1$. Similarly it cannot during reception of the impulse $\varphi3$, which follows it, since the potential of -100 v. would then be received on the wire MW . During the reception of the cycles of impulses corresponding to the impulses $P2$ and $P3$ it cannot operate, since -100 v. is then applied to the rectifier $Rcub1$. If the circuit $C22$ is free, at the time of the simultaneous reception of impulses $\varphi2$ and $P2$, tube $Vb2$ will operate. If the circuit $C22$ is busy the circuits connected to the wire $IW3$ will be tested during the reception of impulse $P3$ and if circuit $C23$ is free tube $Vb3$ will operate.

It will be assumed that tubes $Va2$ and $Vb1$ have operated causing relays $Ra2$ and $Rb1$ to be held. Earth is then connected via make contacts $Ra21$ and $Rb12$ on the outlet 4 in the second group of outlets. This circuit can be used to effect the desired control or signalling.

It will be seen that if it is desired to select a free circuit in the first group, the switch S_c will be set on $Pt1$ and $Va1$ will operate; if it is desired to select a free circuit in the second group, S_c will be set on $Pt2$ and $Va2$ will operate; if it is desired to select a free circuit in the third group, S_c will be set on $Pt3$ and $Va3$ will operate. It will also be seen that the selection of a particular free circuit in the selected group will determine which of the tubes $Vb1$ to 3 will operate. Thus the operated Vb tube will be an indication of which circuit in a group has been selected.

Arrangements may be provided to connect in addition to a source φ , one of the impulse sources $P1$, $P2$, $P3$ to the marking wire MW , by inserting a resistance in the circuit for connection to the wire MW of the source φ and a rectifier in the circuit for connection of source P to the wire MW or vice versa. In this case, the device makes it possible to test a circuit in a particular group since the only tube directly connected to the source P connected to the wire MW is able to operate.

If the test device is placed at a certain distance from the circuits to be tested, it is desirable to reduce the number of interconnecting wires of the two parts of the system. This can be done by replacing the wires shown in dotted lines $TW1$, $TW2$, $TW3$ for individual connection of the tubes $Vb1$, $Vb2$, $Vb3$, to the wires $IW1$, $IW2$, $IW3$, by the common wire TW , shown in continuous lines. In this case, the connections of the wires IW to the wire TW are respectively effected via resistances and rectifiers $Rhp1$, $Rcp1$ — $Rhp2$, $Rcp2$ — $Rhp3$, $Rcp3$. Furthermore, the impulse sources $P1$, $P2$, and $P3$ are respectively connected to the wires $IW1$, $IW2$, $IW3$ via rectifiers $Rdp1$, $Rdp2$, $Rdp3$ and resistances $Rhp1$, $Rhp2$, $Rhp3$. In these conditions the impulses received on the wire $IW1$ will only be received on the wire TW for the duration of one impulse $P1$ and can, owing to this, only cause the operation of the tube $Vb1$. Similarly, the impulses received on the wires $IW2$ and $IW3$ can only respectively cause the operation of tubes $Vb2$ and $Vb3$.

Of course it would be possible without departing from the scope of the invention to replace the cold cathode tubes by any device capable of causing a switching action when a particular potential is applied to its control circuit, in the same way that it is possible to choose for the different potentials such values that the switching device would operate in certain conditions.

What is claimed is:

1. An arrangement for selecting a circuit in one of a plurality of circuit groups, comprising a plurality of sources of pulse trains, arranged in two groups with the pulses of the first group of sources having a repetition rate which is a multiple for the repetition rate of the pulses of the second group of sources, the pulse trains of each group having different time positions within the group, the time duration of all pulses in a group being the same but the time duration of each pulse of the second group being sufficient to encompass a complete cycle of the pulse trains of said first group, means for connecting a different one of said first group of sources of pulse trains to each group of circuits, a plurality of coincidence trigger devices, each having a plurality of inputs and adapted to operate only when voltages at least as great as said pulses are applied simultaneously to all said inputs, said devices being arranged in two groups, the first

group having a number of devices equal to the number of circuit groups and corresponding respectively to said circuit groups, the second group having a number of devices equal to the number 5 of circuits in a group and corresponding respectively to the circuits of a group, means for selectively applying pulse trains from said first group of sources to one input of each of said devices, means for applying pulse trains from said first 10 group of sources respectively to second inputs of the devices of said first group, means for applying pulse trains from said second group of sources respectively to second inputs of the devices of said second group, means for connecting 15 third inputs of the devices of said second group respectively to corresponding circuits of each group of circuits, a plurality of control circuits corresponding to the circuits of said groups, and means controlled by the combination of devices 20 operated for energizing a selected one of said control circuits.

2. An arrangement, according to claim 1, in which the trigger devices comprise electronic discharge paths, each path having an anode, a cathode, and a control electrode, the inputs being 25 connected to the control electrodes, there being one input for each pulse train applied, one of said inputs including a resistance and the others including rectifiers poled so that current flowing through said resistance between said inputs will produce a drop in potential on said control electrode.

3. An arrangement, according to claim 2, in which individual leads are provided for connecting 35 the third inputs of the devices of the second group to corresponding circuits of each group of circuits.

4. An arrangement, according to claim 1, in which a single lead is provided for connecting all 40 the third inputs of the devices of the second group to corresponding circuits of each group of circuits, the connection of each group of corresponding circuits to said single lead comprising a resistance and a first rectifier in series therewith, 45 the rectifier being connected to the single lead and poled in a direction so that current can flow towards said devices, an auxiliary lead including a second rectifier connected to the junction of said resistance and first rectifier, with said second rectifier so poled that current can flow out of said auxiliary lead, and means for applying pulse trains from said second group of sources respectively to said auxiliary leads.

5. An arrangement, according to claim 4, in 55 which individual means is provided for each circuit for breaking the connection between it and a third input of the second group of trigger devices when the circuit is in a predetermined condition.

6. An arrangement, according to claim 5, in 60 which the means for energizing a selected one of the control circuits comprises a plurality of relays, one connected to each device in the first and second groups of devices and arranged to operate when said device operates, the control circuits 65 including contacts of said relays.

7. An arrangement, according to claim 1, in which individual means is provided for each circuit for breaking the connection between it and a third input of the second group of trigger devices 70 when the circuit is in a predetermined condition.

8. An arrangement, according to claim 1, in which the trigger devices comprise electronic discharge paths, each path having an anode, a cathode, and a control electrode, the inputs being 75 connected to the control electrodes, there being

one input for each pulse train applied, one of said inputs including a resistance and the others including rectifiers poled so that current flowing through said resistance between said inputs will produce a change in potential on said control electrode, and in which the means for energizing a selected one of the control circuits comprises a plurality of relays, one connected to each device in the first and second groups of devices and arranged to operate when said device operates, the 10 control circuits including contacts of said relays.
